US0D1092850S

(12) **United States Design Patent** (10) **Patent No.:** **US D1,092,850 S**
(45) **Date of Patent:** **** Sep. 9, 2025**

(54) **STAND FOR HAIR DRIER**

(71) Applicant: **LG Electronics Inc.**, Seoul (KR)

(72) Inventors: **Chulhee Lim**, Seoul (KR); **Minji Seo**, Seoul (KR); **Sanghoon Yoon**, Seoul (KR); **Nahyun Kim**, Seoul (KR)

(73) Assignee: **LG ELECTRONICS INC.**, Seoul (KR)

(**) Term: **15 Years**

(21) Appl. No.: **35/522,006**

(22) Filed: **Aug. 11, 2023**

(80) **Hague Agreement Data**

Int. Filing Date: **Aug. 11, 2023**

Int. Reg. No.: **DM/234724**

Int. Reg. Date: **Aug. 11, 2023**

Int. Reg. Pub. Date: **Aug. 16, 2024**

(30) **Foreign Application Priority Data**

Feb. 15, 2023 (KR) 30-2023-0005687

(51) **LOC (15) Cl.** **28-03**

(52) **U.S. Cl.**

USPC **D28/73; D3/205**

(57) **CLAIM**

The ornamental design for a stand for hair drier as shown and described.

DESCRIPTION

1. Stand for hair drier

1.1 : Perspective

1.2 : Front

1.3 : Left

1.4 : Top

1.5 : Bottom

1.6 : Exploded

1.7 : Perspective view 2

The broken lines depict portions of the stand for hair drier that form no part of the claimed design; reproduction 1.2 is a front view of the claimed design where the back view is a mirror image; reproduction 1.3 is a left view where the right view is a mirror image; reproduction 1.6 is an exploded view showing the state that the upper cover is separated from the lower body of the claiming design; reproduction 1.7 is a perspective view showing that the hair drier and its nozzles, etc. are equipped while the upper cover and the lower body of the claiming design are separated; the brackets in reproductions 1.6 and 1.7 are disclaimed.

1 Claim, 7 Drawing Sheets
